(57) **CLAIM**

The ornamental design for an air blow pipe, as shown and described.

DESCRIPTION

FIG. 1 is a top, front, and right perspective view of an air blow pipe showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings illustrate portions of the air blow pipe which form no part of the claimed design.

The dot-dashed line in the figures defines the boundary of claimed design and forms no part of the claimed design.
